UNITED STATES PATENT OFFICE.

EUGENE SMITH, OF TOOKEE, UTAH.

SASH-CORD FASTENER AND FULCRUM FOR WINDOW-SASHES.

1,358,121.

Specification of Letters Patent.

Patented Nov. 9, 1920.

Application filed January 5, 1920. Serial No. 349,416.

To all whom it may concern:

Be it known that I, EUGENE SMITH, a citizen of the United States, residing at Tooele, in the county of Tooele and State 5 of Utah, have invented certain new and useful Improvements in Sash-Cord Fasteners and Fulcrums for Window-Sashes, of which the following is a specification, reference being had to the accompanying drawings.

10 This invention relates to the art of window frames, wherein the inner sash and parting strips or beads are removable, and particularly to improved means carried by the sash whereby the sash may be swiveled 15 for reversing the sash, so that it can be replaced in a reversed position for cleaning the window pane or for glazing the sash.

As another object of the invention it is the aim to provide means for attaching a 20 sash cord to a sash whereby when the sash is swung inwardly it may swivel so that it can be reversed, and then replaced in the frame for cleaning the outer face of the pane or for reglazing the sash.

25 A further object is to provide a device to obviate the necessity of window cleaners sitting out on the sill of the window, or on supporting shelves, thereby avoiding endangering life.

30 A still further object of the invention is to provide a device of this character especially adapted for use in connection with sashes, which are not slidable but are fixedly arranged in the frame; said device being 35 designed to act as a fulcrum for the sash whereby the sash may be reversed as it is moved inwardly so that the outer face of the pane may be cleaned or the sash reglazed. In this case, it is the aim of the invention to provide a support for the device 40 or fulcrum so that the sash may be swivelly reversed for the purposes intended.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and 55 claimed.

In the drawings:—

Figure 1 is a vertical sectional view through the window frame, showing the upper and lower sashes as disposed on the inner part of the frame and reversed so that 60 the outer face of the panes may be cleaned or the sash glazed or reglazed, and illustrating the preferred form of the connection between the sash cords and the sashes,

Fig. 2 is a transverse sectional view on the 65 line 2—2 of Fig. 1,

Fig. 3 is a vertical sectional view through a window frame, showing the upper and lower sashes in their proper positions, and illustrating a modified form of connection 70 between the sash cords and the sashes,

Fig. 4 is a sectional view on line 4—4 of Fig. 3,

Fig. 5 is an enlarged detail view of the 75 parting strip,

Fig. 6 is a vertical sectional view through a window frame, showing the upper and lower sashes in their proper positions, but illustrating another modified connection between the sash cords and the sashes, 80

Fig. 7 is a view similar to Fig. 6, showing the sashes as having been swung inwardly and reversed and replaced in the frame,

Fig. 8 is a sectional view on the line 8—8 of Fig. 6, showing more particularly the 85 detail construction of the modified connection between the sash cord and the sash, as shown in Fig. 6,

Fig. 9 is a sectional view on line 9—9 of Fig. 6, showing the fastening means for the 90 inside stop, and illustrating the parting strip secured in the groove, and

Fig. 10 is a vertical sectional view through a window frame showing how a non-slidable window sash can be moved inwardly to be 95 reversed for cleaning and other purposes.

Fig. 11 is a detail view showing how the bracket 33 is attached to the side of the window frame.

Referring more especially to the drawings, 1 designates a conventional form of window frame, which is provided with the usual parting and inner sash strips or stops 2 and 3. In fact the parting strip 2 comprises the upper section 4 which is constructed of wood, and the lower section 5 is constructed of sheet metal. The inner sash strip or stop also comprises an upper section 6 and a lower section 7. The lower section 7 of the inside sash stop is detach- 100
105
110

2
ably fastened to the window frame, as shown. In order to accomplish this result, sleeves or bushings 8 are embedded in the frame rails and secured in position preferably by threads, as indicated, though not necessarily, and threaded into these sleeves or bushings are thumb screws 9. In order to not mar the paint or other finish of the inner sash stop section 7, sleeves or bushings 10 are extended into or countersunk in said section. These sleeves or bushings 10 are provided with beads or rolls 11, against which the shoulders 13 of the thumb screws 9 contact. It will be noted that the sleeves or bushings 10 are larger in diameter than the shanks of the thumb screws, in order to permit of an easy passage of the screws through the sleeves or bushings. It is obvious that when the inner sash stop section 7 is detached, it is possible to remove or swing the lower sash inwardly of the room, so that it can be reversed.

The lower section 5 of the parting strip is constructed of sheet metal, U-shaped in cross section, as shown clearly in Fig. 5, and the inner longitudinal edge portions of the side flanges of said parting strip are bent slightly toward each other as shown at 5^a. By this construction, it is possible to start and force the side flanges 5^b of the parting strip section 5 into the groove 5^c of the frame rail, as shown clearly in Fig. 9. This method of attaching the parting strip section 5 is uniform throughout all the illustrations of the device. The lower end of the parting strip section 5 has a lateral ear or bent portion 5^d. When placing the parting strip section 5 in position, the aperture or opening 5^e receives a dowel pin 5^b, which is driven into the base of the window frame, adjacent the lower end of the groove 5^c. After placing the ear or lateral portion 5^d in position, the parting strip section 5 is moved toward and into engagement with the groove 5^c. In fact before inserting the parting strip section 5 in the groove, its side flanges 5^b are bent slightly toward each other, and when the parting strip section 5 is positioned home, the side flanges are brought together, and owing to friction between these flanges and the side walls of the groove, the parting strip section 5 is held securely in place. When the parting strip section 5 is removed, the upper window sash can be lowered, and then swung inwardly and reversed, and placed in the position shown in Fig. 1, so that the outer face of the window pane may be cleaned or a new pane of glass inserted. The lower parting strip section 5 may be removed very easily, by inserting a tool or sharp instrument or the like through any one of the openings or apertures 5^e. The instrument or other tool is passed through both flanges of the section

5, and a pulling action is imparted on the 65 tool, to pull the section 5 out of position.

Referring particularly to Figs. 1 and 2, each of the side rails of the upper and lower sashes 14 and 15 is provided with a cylindrical depression *a* to receive the tubular cylinder *b*. This tubular cylinder is provided with lateral ears *c* which receive screws *d*, in order to hold the cylinder in place. In fact the ears *c* are counter-sunk in the edge of the sash rail. A solid cylinder *e* is loosely 70 guided in the cylinder *b* and has its inner end provided with an annular collar or flange *g* which is designed to contact with the inner end of the cylinder *b* to limit the outward movement of the solid cylinder *e*, 75 when the sash is reversed. In Figs. 1, 2, 3 and 4 the upper and lower sashes 14 and 15 are provided with the usual sash cord receiving grooves *h* and *k* to receive the sash cords *m* and *n*, when the upper and lower 80 sashes are in their proper position.

The outer end portion of the solid cylinder *e* is provided with a transverse opening *q* to receive the lower end of the sash cord. The solid cylinder *e* has a threaded opening *p* extending axially of the cylinder. This opening *p* joins the opening *q* and is designed to receive a threaded plug *s*. This plug *s* has the usual slit or groove *u* in its outer end to receive a screw driver, whereby the plug may be screwed home. A clamping plate *v* is placed through the threaded opening *p*, and in contact with the side of the end of the sash cord. The clamping plate *v* is concaved, so that its marginal edge will bury or sink into the sash cord, and act to clamp the cord in position in the opening *q*. The plug *s* at its inner end is concaved as shown at *w* to engage the clamping plate *v* so as to force it toward the sash cord. By this construction each sash cord is securely and detachably connected to its respective sash. At the present, the solid cylinder *e* is believed to be the most preferable form of connection for the sash cord, particularly in view of the fact that while Fig. 1 discloses the grooves *h* and *k* above the point of connection of the sash cord, it is obvious that they may also be formed below the connection of the sash cord, as in Figs. 6, 7 and 8, whether the sash rail is thick or thin. In other words, with the form of connection shown in Figs. 1 and 2, the sash cord receiving grooves may be formed above and below the connections of the sash cords, as the solid cylinder can be made very small in diameter, in comparison to the tubular sliding cylinder which is shown in the other figures of the drawing.

When it is desired to clean the outer faces of the panes of the upper and lower sashes, the inside stop section 7 and the parting strip section 5 are removed. The

lower sash is then moved inwardly, reversed, and placed in the position shown in Fig. 1. The upper sash is then pulled down and swung inwardly, reversed, and then disposed on the lower part of the window sill, as in Fig. 1. The sash cords engage around the opposite edges of the sash rails as will be obvious from an inspection of Fig. 1. The outer face of the panes of the upper and lower sashes may then be washed and the upper sash turned to assume its proper position and replaced in the frame, and then raised to its normal position. The lower sash is then pulled down from the upper position shown in Fig. 1 and reversed to its normal position and replaced in the window frame. However, before replacing the lower sash, the lower parting strip section 5 is replaced in the manner previously stated. After replacing the lower sash, the lower inside stop section 7 can be re-connected. The outer tubular cylinder *b* in Figs. 1 and 2 is provided with a U-shaped cut away portion *a* shown clearly in dotted lines in Fig. 2 to receive the sash cord when the sash is in its proper position in the frame.

In Figs. 3 and 4 the hollow outer cylinder *b* is provided with a single ear *c'*, which extends downwardly and receives a fastening screw *d* similar to that shown in Figs. 1 and 2. Mounted in the outer tubular cylinder *b* shown in Figs. 3 and 4 is a hollow or tubular cylinder *e*², the inner end of which is provided with an integral collar or shoulder *g*². The wall of the cylinder *e*² has an opening *e*³ provided with an eye-let or sheet metal lining *e*⁴. In this construction, the sash cord is passed through the eye-let or lining and is formed with a knot *n*² to prevent the detachment of the cord. Also in this instance, the cylinder *e*² is provided with the slot 32, which is shown in Fig. 8. This form of connecting the sash cord is particularly adapted for window sashes of the ordinary type, which have their rails very thin, and is also by far a cheaper construction, by reason of the simple way of attaching the sash cord to the inner cylinder by means of the knot. However, to use a knot for securing the cord to the inner cylinder it is necessary to have a larger cylinder than may be used in the construction shown in Fig. 1 or larger than the construction of cylinder shown in Figs. 6, 7 and 8. The outer cylinder *b* in Figs. 3 and 4 is provided with a semi-circular cut away portion or recess *b*², which conforms to the construction of the sash cord receiving groove, so as to permit the cord to engage the eye-let covered opening of the inner cylinder. However, it is not possible to use sash cord receiving grooves below the cylinders *b* in Figs. 3 and 4, by reason of the fact that the ear *c'* extends downwardly.

When the sashes are so positioned it is possible to reverse the sashes and then replace them temporarily in the frame, so that the outer faces of the panes of both sashes may be cleaned or the sashes glazed or reglazed from the interior of the room.

The reversing of the sashes is possible due to the sash cords 16 and 17 being attached to their respective sashes by swivel or fulcrum connections, as indicated in the drawings, particularly in Figs. 6 and 7.

Each connection of a cord to a sash comprises inner and outer cylinders 18 and 19, the inner cylinder being rotatably mounted within the outer cylinder. The outer cylinders of the fasteners of each sash are counter-sunk or extended into the sash rails, as shown, and are provided with diametrically opposite flanges 20 to receive fastening screws 21, to hold the outer casings 19 securely in fixed positions. In order to counter-sink the outer cylinders 19, the side rails of the sash are drilled or bored out to form chambers, which are deep enough to permit the inner ends of the inner cylinders to extend inwardly into the side rails beyond the inner ends of the outer cylinders 19. However, the inner ends of the inner cylinders 18 are provided with annular beads or shoulders 22 adapted to contact with the inner ends of the outer cylinders, to prevent the withdrawal of the inner cylinders entirely, when it is desired to remove the sash cords from their counter-sunk positions in the side rails of the sash. The sash cords 16 are fastened to the walls of the outer ends of the inner cylinders by first passing the ends of the cords through openings or apertures of the inner cylinders, there being clamps 23 secured to the ends of the cords by means of clamping screws 24. The apertures or openings of the inner cylinders have their marginal edges bound or lined with beadings or eyelet rings 25, to prevent the marginal edges of the openings or apertures from cutting the cord which would eventually occur should the openings or, apertures not be lined.

In order that the sashes may be replaced in the frame after having been reversed so that the outer faces of the panes of glass may be cleaned, the outer edges of both side rails of the sashes are provided with grooves 26 and 27 above and below where the sash cords are attached to the sashes. It is obvious that when each sash is in its proper position, the sash cords engage the grooves 26, but when the sash is reversed, and replaced in the frame, the sash cords engage the grooves 27 which are then positioned above the attached ends of the cords. In order that the cords may lie in either set of grooves, diametrically opposite portions of the walls of the outer cylinders adjacent their outer ends are provided with semi-cir-

cular recesses 28 for the reception of the cords.

Referring to Figs. 6, 7 and 8 of the drawings, it will be seen that either one or both 5 of the sashes may be moved inwardly of the room by first having detached the removable sections of the parting strips and inside sash stops. After having swung one or both of the sashes inwardly of the room 10 and then withdrawing the inner cylinders, the sashes may be moved swivelly, using the inner cylinders 18 as trunnions, until the outer faces of the panes face inwardly. The inner cylinders may then be pushed inwardly causing the cords to engage the grooves 27. The sashes may then be replaced temporarily, after which the window cleaner or glazer may proceed to clean the pane, or glaze the same.

20 In Fig. 10, a non-slidable sash 30 is mounted in the window frame and held fixedly but removably in position by the securing strip or stop 31. This strip or stop is fastened in a similar manner to the stops 25 or strips previously described, preferably by the use of thumb screws heretofore referred to, though not necessarily. The sash 30 in Fig. 10 has its side rails provided with the cord attaching or fastening means which 30 have been heretofore described. However, in this instance sash cords are not employed, and furthermore the attaching means, which may be so called in the present instance, simply constitutes a fulcruming means for the 35 sash. The inner cylinders have their outer ends provided with segmental notches or slots 32 which as hereinafter set forth act to straddle suitable supports to permit the sash to be swivelly reversed when the sash stops 40 are removed. It is to be understood that the inner and outer cylinders constitute trunnion means for slidable window sashes as in Figs. 1 and 2 and 6 and 7, or when used on a single non-slidable sash as in Fig. 10, and 45 that the inner cylinders are supplied with the notches or slots so that the fulcruming trunnion means can be used in either case. In other words, the fulcruming trunnion means constitutes an article of manufacture 50 comprising the inner and outer cylinders telescopically and swivelly united with means on the inner end of the inner cylinder to limit the inner cylinder in its outward movement, in combination with the sash 55 cord attaching means and the segmental slots or notches so that the fulcruming trunnion means may be used in connection with slidable sashes where sash cords may be attached to the inner cylinder, or on a non-slidable 60 sash where the notches or slots engage suitable supports, so that in either case the sashes may be moved inwardly and swivelly reversed after the stops have been removed.

Furthermore, referring to Fig. 10, it will 65 be noted that there are brackets 33 connected

to the side rails of the frame, as indicated at 34 and 35. These brackets are in the form of metallic strips and their outer ends are provided with openings or apertures 36. Suitable braces for the brackets 33 are provided, and each brace comprises a tubular section 37 and a rod section 38 which are telescopically united. A thumb screw 39 is employed for holding the rod section in different telescopically adjusted positions since 75 the thumb screw threads through the tubular section. When the brace is employed, the tubular section rests upon the sill of the window frame, as illustrated, while the outer end of the rod section is fastened to the 80 outer end of the bracket by means of a bolt or nut 40. The bolt may pass through any one of the openings or apertures 36 so as to connect the brace to the bracket in different 85 adjusted positions. Owing to the adjustable connection of the brace to the bracket and owing to the adjustable connections between the two sections of the brace, it is possible to hold the bracket in different adjusted positions relatively to the frame so that when the 90 sash is moved inwardly of the room it may be held in different positions. Ordinarily the arch plate 35^a is fastened to the window frame as a fixture and when it is desired to use the supporting brackets 33 the inner 95 right angle ends of these brackets are inserted between the arch plates and the window frame after which the thumb screws 35 are engaged through the arch plates and the right angle ends of the bracket. However, 100 the bracket may be adjusted relatively to the window frame and in order to do this the thumb screw 35 and the screws 34 may be removed, the arch plates 35^a replaced in a 105 higher or lower position on the side of the frame and the brackets may then be attached. When the arch plates are so adjusted it is 110 obvious that the braces should be adjusted in order to accommodate the brackets in their different positions.

Obviously the brackets 33 may be used in connection with window sashes which are slidable and which are carried on sash cords as well as in connection with non-slidable 115 sashes. When the brackets 33 are used in connection with slidable sashes where the sash cords are employed, the brackets will act to steady the sashes when they are swivelly reversed even though the sash cords remain attached to the fulcruming trunnion means. As previously stated, when using the cylinders as shown in Fig. 10 there are no sash cords employed. It is obvious that when the sash holding strip or stop 31 is removed, the window sash may be lifted inwardly of the room from the frame after which the inner cylinders 18 may be withdrawn. When the cylinders are so positioned, their segmental notches 32 may straddle the upper edge portions of the brackets 120 125 130

33 allowing the sash to slide inwardly of the room. When positioned sufficiently inwardly of the room, it is possible to swivelly reverse the sash owing to the inner cylinders 5 18 being held stationary by means of the notches 32. The inner cylinders act as trunnions, on which the outer cylinders (which are counter-sunk in the side rails of the sash) may rotate. After the sash has been swivelly 10 reversed, it is possible to temporarily replace the sash so that the window cleaner may wash the outer face of the pane (which then faces inwardly of the room) or glaze the sash.

15 The outer cylinders 19 adjacent their outer ends are provided with semi-circular recesses 28 for the reception of the cords 16 when the inner cylinders are extended inwardly to their full counter sunk positions.

20 The invention having been set forth, what is claimed as new and useful is:—

1. The combination with a window frame, provided with removable sash stops, of a sash mounted in said frame, fulcruming trunnion means on which the sash may be swivelly reversed when the stops are removed and the sash moved inwardly, means for supporting the fulcruming trunnion 25 means, said fulcruming trunnion means comprising inner and outer cylinders telescopically united and being countersunk in the side rails of the sash, and means carried by the inner ends of the inner cylinders to 30 contact with the inner ends of the outer cylinder to hold the inner cylinders in their outward movements.

2. The combination with a window frame which is provided with removable sash 40 stops, of a sash in said frame, fulcruming trunnion means on which the sash may be swivelly reversed when the stops are removed and the sash moved inwardly, means for supporting the fulcruming trunnion 45 means, said fulcruming trunnion means comprising inner and outer cylinders telescopically united and being countersunk in the side rails of the sash, means carried by the inner ends of the inner cylinders to 50 contact with the inner ends of the outer cylinders to limit the inner cylinders in their outward movements and means for securing the outer cylinders in their countersunk positions.

55 3. The combination with a window frame including removable sash stops, of a sash mounted in said frame, fulcruming trunnion means axially alined and swivelly mounted on the side rails of the sash, said 60 fulcruming trunnion means comprising inner and outer cylinders, the outer cylinder being countersunk in the side rails of the sash for telescopically and swivelly receiving the inner cylinder whereby the inner 65 cylinder may rotate and move telescopically,

and means operatively engaging with the inner cylinders for supporting the fulcruming trunnion means.

4. The combination with a window frame including removable sash stops, of a sash mounted in said frame, fulcruming trunnion means axially alined and swivelly mounted on the side rails of the sash, said fulcruming trunnion means comprising inner and outer cylinders, the outer cylinder 70 being countersunk in the side rails of the sash for telescopically and swivelly receiving the inner cylinder whereby the inner cylinder may rotate and move telescopically, and means operatively engaging with the 80 inner cylinders for supporting the fulcruming trunnion means, and means carried by the inner ends of the inner cylinders to limit them in their outward telescopical movements.

5. The combination with a window frame including removable parting and inner sash stops, of upper and lower sashes mounted in said frame, sash cords therefor, fulcruming trunnion means swivelly connecting the 90 sash cords and the sashes whereby the sashes may be swivelly reversed when the stops are removed and the sashes moved inwardly, said fulcruming trunnion means comprising inner and outer cylinders countersunk in the 95 side rails of the sashes and telescopically united whereby the inner cylinders may move telescopically, means carried by the inner ends of the inner cylinder to limit them in their movements, and means for 100 attaching the sash cords to the outer ends of the inner cylinders, the outer cylinders having means for the reception of parts of the cords to permit the cords to countersink in the side rails of the sashes.

6. The combination with a window frame including removable parting and inner sash stops, of upper and lower sashes mounted in said frame, fulcruming trunnion means comprising inner and outer cylinders, the 110 latter being countersunk in the side rails of the sashes, and swivelly and telescopically receiving the former, whereby the sashes may be swivelly reversed when the stops are removed and the sashes moved inwardly, 115 and means operatively engaging with and supporting the inner cylinders when moved outwardly telescopically when the sashes are swivelly reversed.

7. The combination with a window frame 120 including removable parting and inner sash stops, of upper and lower sashes mounted in said frame, fulcruming trunnion means comprising inner and outer cylinders, the latter being countersunk in the side rails of the 125 sashes, and swivelly and telescopically receiving the former, whereby the sashes may be swivelly reversed when the stops are removed and the sashes moved inwardly, and means operatively engaging with and sup- 130

porting the inner cylinders when moved outwardly telescopically when the sashes are swivelly reversed, and means carried by the inner ends of the inner cylinders to limit them in their outward telescopical movements.

8. The combination with a window frame including removable parting and inner sash stops, of upper and lower sashes mounted in 10 said frame, sash cords therefor, fulcruming trunnion means swivelly connecting the sash cords and the sashes whereby the sashes may be swiveled reversely when the stops are removed and the sashes moved inwardly, 15 said fulcruming trunnion means comprising inner and outer cylinders countersunk in the side rails of the sashes and telescopically united whereby the inner cylinders may move telescopically, means carried by 20 the inner ends of the inner cylinders to limit them in their movements, and means for attaching the sash cords to the outer ends of the inner cylinders, the outer cylinders having means for the reception of parts of the 25 cords to permit the cords to countersink in the side rails of the sashes, the side rails of the sashes above and below the fulcruming trunnion means having grooves to receive said cords when the sashes are in their 30 proper or reversed positions.

9. The combination with a window frame including removable sash stops, of a window sash removably mounted in the frame, opposite axially alined telescopical ful- 35 cruming trunnion means carried by the sash whereby the sash may be swivelly reversed, sash cords connected to the fulcruming trunnion means, means for the reception of the sash cords when the sash is reversed, 40 whereby the sash may be temporarily replaced in the window frame in a reversed position while the stop is removed.

10. The combination with a window frame including removable sash stops, of a window sash removably mounted in the frame, opposite axially alined fulcruming trunnion means carried by the sash whereby the sash may be swiftly reversed, sash cords connected to the fulcruming trunnion means, 45 means for the reception of the sash cords when the sash is reversed, whereby the sash may be temporarily replaced in the window frame in a reversed position while the stop is removed, said fulcruming trunnion means

comprising inner and outer cylinders, the outer cylinders being countersunk in the side rails of the sash and telescopically and swivelly receiving the inner cylinders, and means connecting the inner cylinders and the sash cords.

11. The combination with a window frame including a removable sash stop, of a window sash removably mounted in said frame, said frame having sash cords, fulcruming trunnions oppositely and axially alined and swivelly and slidably mounted in the side rails of the sash, means connecting the sash cords to the trunnions, said means comprising an opening transversely through the trunnion and an opening axially through the outer end of the trunnion and connecting with the transverse opening which receives the end of the sash cord, and means clamped to the end of the sash cord and engaging the wall of the trunnion to hold the cord connected.

12. As an article of manufacture, fulcruming trunnion means for window sashes, said fulcruming trunnion means comprising inner and outer cylinders, the latter adapted to be countersunk in the side rails of the sash and telescopically and swivelly receiving the former, the inner cylinder having means permitting a sash cord to be attached thereto, the inner cylinder having means to rest upon and straddle a support when the inner cylinder is moved telescopically outwardly from the outer cylinder.

13. As an article of manufacture, fulcruming trunnion means for window sashes, 90 said fulcruming trunnion means comprising inner and outer cylinders, the latter adapted to be countersunk in the side rails of the sash and telescopically and swivelly receiving the former, the inner 95 cylinder having means permitting a sash cord to be attached thereto, the inner cylinder having means to rest upon and straddle a support when the inner cylinder is moved telescopically outwardly from the 100 outer cylinder, the inner end of the inner cylinder having means to limit the same in its outward movement, the outer cylinder having attaching ears whereby it may be connected to the side rail of the sash.

In testimony whereof I hereunto affix my signature.

EUGENE SMITH.
